UNITED STATES PATENT OFFICE.

FRANK L. SLOCUM AND CHARLES C. STUTZ, OF PITTSBURGH, PENNSYLVANIA,
ASSIGNORS TO SYNTHETIC HYDROCARBON COMPANY, OF PITTSBURGH,
PENNSYLVANIA, A CORPORATION OF DELAWARE.

APPARATUS FOR TREATING HYDROCARBONS.

1,304,211.

Specification of Letters Patent. Patented May 20, 1919.

Application filed April 13, 1916. Serial No. 90,851.

To all whom it may concern:

Be it known that we, FRANK L. SLOCUM and CHARLES C. STUTZ, residing at Pittsburgh, in the county of Allegheny and State 5 of Pennsylvania, citizens of the United States, have invented or discovered certain new and useful Improvements in Apparatus for Treating Hydrocarbons, of which improvements the following is a specification.

The invention described herein relates to apparatus adapted to be used in the treatment or cracking of hydrocarbons in the vapor phase, and has for its object the removal and segregation of carbon formed during the treatment without interruption to continuity of the operation. The invention is hereinafter more fully described and claimed. The cracking process to which the 15 apparatus is particularly applicable is fully described in Bulletin 114, *Petroleum Technology* 29, Department of the Interior.

In the accompanying drawing forming a part of this specification, Figure 1 is an 20 elevation of an apparatus embodying our improvements as applied to a plurality of cracking tubes; and Fig. 2 is a sectional elevation showing the lower portion of a cracking tube and the chamber into which the 25 various products formed in the tube are discharged.

As shown in Figs. 1 and 2, the lower side of the cracking tubes 1 are secured to a casting in which is formed a chamber 2, 30 directly under the tube so that the carbon, gases, vapors, etc., will pass freely into said chamber. The stirring rod 3 which is described and claimed in an application filed May 20, 1915, Ser. No. 29,336, is provided at 35 its lower end with a shoe 5, having in its underside an angularly shaped socket for the reception of a correspondingly shaped plug 6 on the upper end of the driving shaft 7, which is inclosed in a tube 8. This tube is provided internally with bearings 9 for the driving 40 shaft and has its upper end supported by sleeve 10, carried by arms 11, integral with the walls of the chamber 2, while the lower end of the tube is secured to a block 45 12, fitting in an opening in the lower end of the chamber. This construction permits

of the easy removal of the driving shaft and its inclosing tube.

The stirring rod and its driving shaft have their axes coincident with the axis of 55 the tube and the chamber, and in order to prevent the carbon, etc., discharged from the open lower end of the tube, from adhering to the tube surrounding the driving shaft and as far as possible to pass directly to the 60 bottom of the chamber 2, a distributor preferably in the form of an umbrella shaped casting 4 is arranged below the open lower end of the tube 1 and is in the normal operation of the machine supported by the upper 65 end of the driving shaft 7 so as to rotate therewith. When the driving shaft and its inclosing tube are removed the umbrella will be supported by the sleeve 10.

The chamber 2 is provided, adjacent to 70 its upper end, with an outlet 13 for gases and vapors generated in the tube 1, said outlet being adapted to be connected with suitable condensing apparatus. At its lower end, the chamber is provided with two 75 valved outlets 14 and 15, for the discharge of carbon and liquid products. As shown in Fig. 1 one of the valved outlets is connected by a pipe 16 to a chamber 17 and the other outlet by a pipe 16^a to a chamber 80 17^a. These pipes are so connected to the segregating chambers 17^a and 17, as to discharge the mingled carbon and oil into one 85 end of troughs 18 and 18^a, which are divided into compartments by baffle plates 19 and 20. As the liquid and the carbon are discharged into the first compartment, the greater part of the latter will settle down 90 therein, but the oil will flow over the baffle 19 into the second compartment, wherein carbon, carried by the oil over the first baffle, will settle down. The bottom of the third compartment is perforated to allow 95 the liquid to drain out into the chambers from which it is discharged, through the 100 valved outlet.

When one of the troughs has been sufficiently charged with carbon, the valve in the outlet from chamber 2, connected with the chamber containing a charged trough, 100 is closed, and the valve in the outlet connected to the other trough containing cham-

ber is opened. As soon as the valve controlling flow to the first chamber is closed, the head of said chamber is removed and the charged trough is drawn out, and the 5 carbon removed, and the trough returned to the chamber. Before removing the head from the chamber, the liquid contained therein is discharged.

As the carbon, etc., may adhere to the 10 surface of the umbrella, or become lodged in the chamber 2 or in the pipes leading therefrom, provision is made for cleaning the umbrella and washing along any carbon which may have lodged in any portion of 15 the apparatus, by means of jets of oil resulting from the condensation of vapors flowing from tube 1.

In the construction shown, a pump diagrammatically represented at 21, is connected by a pipe 22 to the segregating chamber 17, and to the segregating chamber 17, by a pipe 23, the pipes 22 and 23 being provided with valves so that when one of the 20 chambers is to be opened for the removal of its trough, the connection between the chamber and pump may be closed. The discharge port of the pump is connected to a pipe 24, having a series of branches, 25, 26 and 27, the branch 25 having a valved 25 connection 28 to the upper portion of the collecting chamber, the connection 28 being so arranged as to direct a stream of liquid onto the surface of the umbrella. The branch 26 has a valved connection 29, to the 30 lower portion of the collecting chamber, the connection being so arranged as to wash the carbon, etc., into the trough through the outlets 14 and 15.

As shown, a plurality of tubes 1 and collecting chambers have their outlets 14 connected to a common pipe 30, and the outlet 15 to a common pipe 31, said pipes 30 and 31 being connected respectively to the pipes 16 and 16^a as shown in Fig. 1. When a plurality of chambers are thus connected to pipes 30 and 31, the branches 25 and 26 from the main pump line 24, have valved connections 28^a and 29^a to the other collecting chamber 2 and the branch 27 is so connected to the ends of the common pipes 30 and 31 as to wash the carbon toward and into vertical pipes 16 and 16^a.

As the tube 1 discharges into the chamber 2, the latter will contain gases and vapors 55 and while the material is subjected to such conditions in the tube 1 as are most favorable for the production of particular type of hydrocarbons, having certain characteristics and a certain boiling point, hydrocarbons 60 having other and higher boiling points will also be produced. In order to effect a partial segregation of the hydrocarbons, in accordance with their boiling points, it is preferred to so reduce the temperature of the

chamber 2 as to effect a condensation of the 65 vapors of hydrocarbons having a relatively high boiling point. To this end, the chamber 2 is surrounded by a jacket 32 through which a cooling fluid as air is caused to flow.

We claim herein as our invention:

1. In an apparatus for cracking hydrocarbons, the combination of a heating tube, a chamber for the reception of material discharged from said tube, said chamber being 70 provided with an outlet for the escape of gases and vapors, and an outlet for the removal of solids and liquids, and means for returning discharged liquids to said chamber to insure the removal of the solids.

2. In an apparatus for cracking hydrocarbons, the combination of a treating tube, means for removing deposits from the walls of the said tube, a chamber for the reception of material discharged from said tube, said chamber being provided with an outlet for gases and vapors and an outlet for the removal of solids and liquids, means for reducing the temperature of said chamber below the boiling point of a portion of the 80 vapors discharged from the treating tube, and means for returning discharged liquid to said chamber to insure the removal of the solids therefrom.

3. In an apparatus for cracking hydrocarbons, the combination of a treating tube, means for removing deposits from the inner surface of said tube, a chamber for the reception of material discharged from said tube, said chamber being provided with outlets for the removal of products received from the tube, means for segregating the 90 solids and liquids removed from the chamber, and means for returning liquid to the chamber to insure the removal of the solids.

4. In an apparatus for cracking hydrocarbons, the combination of a plurality of treating tubes, a like number of chambers for receiving material discharged from the tubes, said chamber being provided with 100 outlets for the removal of products received from the tubes, a plurality of means of segregating the solids and liquids discharged from the chambers, each segregating means being connected to a plurality of chambers, 110 and means for withdrawing liquid from the segregating means and returning it to a plurality of chambers to insure the removal of the solids.

5. In an apparatus for cracking hydrocarbons, the combination of a treating tube, a chamber for the reception of the material discharged from the tube, said chamber being provided with outlets for the discharge of products received from the tube, a segregating chamber having a removable trough for the reception of solids, and means for withdrawing liquids from the segregating

receptacle and returning it to the chamber to insure removal of solids therefrom.

6. The method herein described which consists in discharging the products resulting from cracking hydrocarbon vapors in a heated tube, into a chamber, condensing a portion of the vapors in said chamber, utilizing a portion of the liquid so formed to re-

move solids from the chamber and separating the solids from the liquids.

In testimony whereof, we have hereunto set our hands.

FRANK L. SLOCUM.
CHARLES C. STUTZ.
